UNITED STATES PATENT OFFICE.

FRANK DZIERZENGA, OF NEW YORK, N. Y.

AUTOMATIC GAS CUT-OFF.

Application filed January 6, 1925. Serial No. 903.

To all whom it may concern:

Be it known that I, FRANK DZIERZENGA, citizen of Czechoslovakia, and resident of New York city, in the county of New York and State of New York, have invented certain new and useful Improvements in Automatic Gas Cut-Offs, of which the following is a specification.

My invention relates to automatic gas cut-offs and has a particular reference to thermostatic devices adapted to close the gas admitting valve if the flame becomes extinguished.

The object of my invention is to provide an automatic device which could be relied upon to stop the flow of gas to the burner in case the flame becomes accidentally extinguished, thereby preventing a danger of gas poisoning or even explosions.

For this purpose I am using a thermostatic element composed of a spiral made of two metals with different temperature coefficients. I connect this spiral with a valve or a cock in such manner, that the movement of this spiral, caused by the unequal reaction to the temperature changes by the metals composing this spiral, closes the valve when the device is cooled off and keeps it open as long as it is kept hot from the burning flame.

I further provide a mechanism whereby the valve may be opened when the mechanism is cold, by locking the thermostatically controlled closing mechanism, and I also provide a mechanism to release said locking device when the mechanism becomes heated from the flame.

My invention is more fully described in the accompanying specification and drawing in which—

Fig. 1 is a sectional elevation of my cut-off, Fig. 2 is an outside view of same, Fig. 3 is a crosssection on the line 3—3 of Fig. 1, Fig. 4 is a view of the valve gear, Fig. 5 is a partial sectional view of valve mechanism, Fig. 6 is a detailed view of the valve, Fig. 7 is a sectional elevation of a modified construction, Fig. 8 is another view of same, Fig. 9 is a detailed view of releasing mechanism, Fig. 10 is a view of the releasing key, Fig. 11 is a view of the thermostatic element, Fig. 12 is a sectional elevation of a modified device, Fig. 13 is an elevation of same, and Fig. 14 is a crosssection of same taken on the line 14—14 of Fig. 12.

My automatic gas cut-off consists of a burner 1 with a flame tip 2. The other end of the burner is provided with threads 3 adapted to fit a gas pipe 4. A valve 5 is fitted in the rear portion of the burner and is provided with a flat upper portion or head 6. This head has lugs 7 adapted to touch the post 8 which thereby limits the movements of the valve. The central aperture 9 in the valve is placed in such manner that it coincides with the aperture 10 in the burner, when one of the lugs 7 strikes the post 8.

Two smaller lugs 11 at the other end of the top plate 6 form a slot 12 between them adapted to engage a cam 13 mounted on a pin 14. This pin is supported on a lug 15 attached to a gear 15. This gear is attached to a collar 16 and can turn on the cylindrical surface of the burner 1. The cam 13 has a lug 17 adapted to bear against the surface of the gear 15 thereby preventing this cam from turning in this direction. It can be turned, however, in the opposite direction against the tension of a spring 18 placed between the lug 19 of the cam and the gear 15.

A ratchet segment 20 is attached to the top of the valve 5 and is in mesh with a corresponding ratchet 21 on a gear 22. This gear has a central shaft 23 placed coaxially with the valve 5 and mounted rotatively in its upper portion (bearing 24). It is provided with a cone 25 in contact with a release rod 26. This rod can slide through an end aperture in the post 8 and through an end plate 27 attached to the rear end of the burner 1. The outside end of the release rod 26 is provided with a collar 28 and a thumb head 29. The collar rests against a spring 30 placed in a partly closed cylindrical chamber 31 attached to the plate 27.

By pressing against the thumb head 29 the end of the rod 26 forces the cone 25 up against the tension of the spring 32 attached with one end to the top of the post 8 and pressing against the central portion of the gear 22 around the shaft 23. This movement brings the gear 22 out of engagement with the gear 15.

The collar 16 is retained in its place by means of a stationary collar 33 fastened to the burner 1 by means of a screw 34.

A thermostatic spiral spring is placed coaxially with the burner 1 and is made of an

outer spring 35 made of some metal having a high temperature coefficient (that is having a high coefficient of expansion due to temperature variations), and of an inner 5 layer 39 made of some metal having a low temperature coefficient. This arrangement causes the spring to wind itself with the increase in temperature and to become unwound when the temperature decreases.

10 The left end of the spring 35 is attached to the rotating collar 16 by means of a screw 36. The other end is attached to a stationary collar 37 fastened to the burner with a screw 38, with a screw 72.

15 The right end of the burner is attached to a front plate 39' provided with apertures 40 in order to admit the hot air from the burner to the thermostatic spring 35. A shell 41 encloses the burner and the mechanism. It may be provided with a side chamber 42 for the gear 22. A funnel 43 is attached to the front end of the shell or casting 41 with a vent 44 for the air and provides a mixing chamber for the gas with 25 the outside air.

A locking link 45 is attached to the collar 16 on a pin 46. A spring 46' tends to push this link against the gear 15.

The end of this pin extends through a 30 slot 47 in the casing 41 and can move in this slot with the movement of the spring 35 and collar 16 with the gear 15. The locking pin takes position 45' when the spring is cold.

35 The locking mechanism consists of a wedge shaped cam 48 adapted to press on the locking link 45 and attached to a locking rod 49. This rod is placed inside of a guiding tube 50 passing through the rear 40 plate 27 and is provided with a collar 51 and a thumb head 52. A spring 53 is placed between the collar and the tube 50 and is enclosed in a housing 54.

The operation of my device is as follows. 45 With the spring 35 cold, the locking link 45 takes a position 45' (Fig. 2), the valve being turned to a closed position Fig. 5. By pressing against the thumb head 52 of the locking device, the cam 48 will force the link 50 up the slot 47, winding the spring 35, until the link reaches the side pocket 55 and gets wedged there in a position 45'' under 55 action of the spring 35 (the spring is shown right hand wound). In this position the valve is turned so that the upper lug 7 strikes the post 8, and the central aperture 9 coincides with the aperture 10 in the body of the burner 1 (Fig. 6). The gas will then pass through the burner to the tip and may 60 be ignited at the mouth of the funnel 43.

It should be noted that the movement of the valve 5 is accomplished through gears 15 and 22 and through cam 13 and slot 12.

65 The spring 35 winds itself after it becomes heated from the burner and moves the link

45 out of the pocket 55. The spring 46' then pushes the link into the slot 47 into a position 45''. From this position the link will move up the slot until it finally reaches the extreme position 45'''.

70 From the examination of the Fig. 6 it may be seen that the cam 13 is free to move up out of the slot 12, when the valve is in a working position as shown. The gear 15 will accordingly turn further under action 75 of the spring 35 until a thermostatic balance is established with the locking link 45 in a position 45'''.

The gear 22 will also turn, the ratchet teeth 21 sliding over teeth 20, their taper 80 being in the direction of movement, and snapping back under action of the spring 32.

Should the flame at the burner become extinguished, however, the spring will cool 85 off and will unwind itself, rotating the gear 15; also the gear 22 and the valve 5 until the lower lug 7' strikes the post 8, with the aperture 9 out of register with the aperture 10. The gas flow will be then stopped, and the locking pin moved to some intermediate 90 position 45''. The further movement will be then stopped, the spring 35 remaining under tension.

In order to set the burner in operation 95 again it is necessary to push against the releasing rod 26 raising the gear 22 out of mesh with the gear 15 and disconnecting the ratchet wheels 21 and 22. The spring 35, being thereby released, snaps to its extreme 100 position to the left, the cam 13 passing on the other side of the lugs 11 by swinging on the pin 14 against the tension of the spring 18. The locking pin takes position 45', and the whole mechanism is ready and set, the valve being closed. In order to open it it is 105 only necessary to press against the thumb head 52 of the locking mechanism.

The gear 15 may be provided with extra long teeth, as shown in Fig. 1, fitting loosely 110 between the teeth of the gear 22, so that the teeth of the gears 15 and 22 may remain in mesh while the ratchet teeth are being disengaged. It is evident, however, that such an arrangement is not necessary, and the device 115 is operative even when the gears are fully disengaged by the action of the release rod 26.

The gear and ratchet mechanism is added 120 in order to make the thermostatic device quick acting, as the valve is closed immediately after the spring begins to cool off, or, in practice, with a properly constructed device, in less than a second.

125 It is possible, however, to simplify the mechanism, when such rapidity of action is not required. Fig. 7 shows such a modified mechanism. Here the spring 32 presses directly against the valve 5, serving only to keep this valve in place. The gears and ratchets are omitted, and the lugs 11 engage 130

a cam 56 attached to the rotating collar 16. The spring is made in the form of an open cylindrical shell 57, attached with one corner to the stationary collar 37 and with the other to the rotating collar 16.

Instead of a single locking cam 48, two cams 58 and 59 may be employed, attached to the individual locking rods 60 and 61 with collars 62 and 63 and with retrieving springs 64. The thumb heads are omitted, and in order to push the locking link 45 into an open locked position 45'', both rods must be pushed at once and to the same extent, and this can be accomplished only by means of a special key 65. The legs 66 of this key (Fig. 10) are made to fit exactly into the openings in the housings 54.

It is easy to see, that with this arrangement the valve cannot be opened, if only one of the rods is pushed. For instance, if the lower rod 60 is pushed only, then the link 45 will be moved only a short distance and will not reach the pocket 55. If the upper rod 61 only is pushed, it will move above the link 45 without any effect on it. And only when the key 65 is used, will both rods be moved at once, presenting an even cam surface, the same as if there was one single cam, as in Fig. 1.

This arrangement makes the burner fool proof against being used or operated by unauthorized persons, thereby adding to the safety of the device.

The burner in the form as described is best suited for use with stoves, ranges, furnaces etc. For gas lamps a simpler device may be used, as shown in Fig. 12.

This lighting burner consists of a tubular body 67 with threads 3 at the lower end adapted to fit a gas pipe 4. The upper end is provided with an inverted conical valve seat 68 adapted to fit a conical valve 69 with a burner tip 2. A screw 70 with a helical spring 71 tends to keep the valve 69 in engagement with the body 67. The valve 69 is provided with an aperture 73 in line with an aperture 74 in the body 67, the latter aperture being elongated as shown in Fig. 14. The burner tip 2 is provided with a plurality of small holes 75 for spreading the flame in a fan like shape.

The base of the body 67 is provided with a flange 76 and a stationary ring 77 which may be clamped in any position on the body 67 with a screw 78. A thermostatic spiral spring 79 is attached with one end to the ring 77 (pin or screw 80) and to the valve 69—with the other, the end of the spring fitting into a slot 81. A housing or shell 82 is fitted over the spring, being clamped to the stationary ring with a screw 83.

A locking link 84 is pivotally attached to the valve 69 on a pin 85 and extends outside through a slot 47. The end of the link 84 is provided with a thumb head or ball 86,

which also serves as a weight, tending to keep the link down. A pocket 55 is provided above the slot 47 for the link 84.

The operation of this device is as follows. With the spring 79 cold, the link 84 remains in the extreme right position (provided, that the metal with high temperature coefficient is on the outside of the spring 79, and a metal with low temperature coefficient 87—on the inside, and that the spring is wound left hand, as shown). The valve then remains closed, the hole 73 moving to a position 73' (Fig. 14), out of register with the hole 74.

In order to open the valve the link 84 is moved against the tension of the spring 79 and then raised into the pocket 55, remaining there being pressed against one side of the pocket by the spring tension. The hole 73 takes then position against the hole 74, as per Fig. 14, the gas will flow through the valve, and may be then ignited at the burner tip.

The heat from the flame will cause the spring 79 to wind around the burner, the outside metal expanding more rapidly than the inside layer 87. The pressure on the locking pin 84 will be then released, and the weight 86 will cause it to drop into the slot 47. Further movement of the spring will move the link farther to the left in the slot 47.

As soon as the flame is extinguished, the resultant cooling and contraction of the outer layer of the spring 79 will move the link to the right along the slot 47 with the valve 69, until the hole 73 comes out of register with the hole 74, taking inoperative position 73'. The flow of gas will be then stopped, even if the ordinary valve somewhere on the gas pipe 4 was not closed manually.

It is easy to see, that, the hole 74 being oblong, the gas flow will not be stopped with the valve rotation to the left, and only when the valve rotates to the right with the link 84 moving to the right from the pocket 55, will the valve be closed.

Important advantages of my automatic valve are that it operates quickly and automatically, can be set in the operating position quickly by simply moving the link into the locking pocket, is simple in construction, and can be easily adjusted for different working conditions.

I claim as my invention:

1. In an automatic gas stopper, the combination with a burner, a valve in a cooperative relation with said burner, a spring consisting of two metals with different temperature coefficient and placed concentrically with said burner, an operative connection between said spring and said valve, a locking link operatively connected with said valve and said spring, a shell around said burner, a slot in said shell for said link, said slot being arranged in the line of movement of

said link under action of said spring, a locking pocket connected with said slot, said link being adapted to be placed in said locking pocket when said valve is opened, means to release said link from said pocket when said spring becomes hot.

2. In an automatic gas stopper, the combination with a burner, a valve in a cooperative relation with said burner, a spiral spring 10 encircling said burner, one end of said spring being attached to said burner, an operative connection between the other end of said spring and said valve, a locking link in a cooperative relation with said valve and said 15 spring, a shell enclosing said burner, a slot in said shell for said link, a pocket in said slot for said link, said pocket being located so that when said link is locked in it, said valve is opened, and means to release said 20 link when said spring becomes hot.

3. In an automatic gas stopper, the combination with a burner, a valve in a coopera-

tive relation with said burner, a bimetallic spring encircling said burner, said spring consisting of two metals of different temperature coefficients, an operative connection between said spring and said valve, said spring being adapted to close said valve when said burner is cold, a locking link in a cooperative relation with said spring, a shell 25 enclosing said burner, and provided with a slot for said link, a locking pocket in said slot for said link, said spring being adapted to keep said link locked in said pocket when said burner is cold, the valve being adapted to be opened when said link is locked in said pocket, means to release said link when said spring becomes hot, and means to keep said valve open while said spring is maintained hot by said burner. 30 35

Signed at New York in the county of New York and State of New York January 40
